O. ARAM

STOKER

Filed June 4, 1923

UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

STOKER.

Application filed June 4, 1923. Serial No. 643,367.

This invention relates to multiple retort underfeed stoker furnaces in which fuel-feeding retorts and rows of tuyères are alternately arranged in parallel relation and inclined downwardly from the front wall of the furnace, and it has for an object to provide in a furnace of the character designated, a means for introducing into the green fuel entering the furnace a supply of highly heated air for the purpose of facilitating fuel ignition.

Another object of my invention is to provide in a furnace of the character designated a durable front wall construction including means for defining the fuel openings between the ram boxes and the retorts and for supporting the refractory front wall of the furnace above the fuel openings.

A further object of my invention is to provide for the circulation of air from the tuyère air boxes of the stoker furnace through the wall structures defining the fuel openings into the retorts for the dual purpose of cooling the wall members and of pre-heating the air for assisting in the ignition of the entering fuel.

A still further object of my invention is to provide a front-wall air-box construction for distributing air pre-heated in the wall-supporting structures to the entering fuel and to the combustion zones of the furnace.

These and other objects of my invention are attained by means of a stoker construction embodying the features herein described and illustrated in the drawings accompanying and forming a part hereof wherein:

Fig. 1 is a fragmentary view in longitudinal section of the front end of an underfeed stoker furnace embodying my invention, taken on the line I—I of Fig. 3;

Fig. 2 is a fragmentary view in longitudinal section taken on line II—II of Fig. 3;

Fig. 3 is a fragmentary view, in part in transverse section taken on the line III—III of Fig. 1, and in part in elevation looking at the front wall from the interior of the furnace;

Fig. 4 is a view from the interior of the furnace of one of the hollow wall supporting casings, showing the openings for the ingress and egress of air; and,

Fig. 5 is a view in elevation of one of the air distributing boxes.

Referring now to the drawing, I show a portion of an underfeed stoker composed of a plurality of retorts 11 and tuyère banks 12. The tuyères 13 of the tuyère banks 12 are mounted upon the upper edges of side walls 14 of the retorts 11 which walls define with the tuyères air boxes 15. The retort side walls 14 may be supported upon angle beams 18 which extend the length of the underfeed grate and which in turn are supported at the front of the furnace by the castings 19. The castings 19 preferably have spaced recesses 21 and lugs 22 therebeneath for positioning and carrying the angle beams 18. Lateral projections 23 at the ends of the castings 19 serve, when a plurality of sections are assembled, to provide a proper spacing of the retort elements.

As shown in Figs. 1 and 2 of the drawing, the angle beams 18 project forwardly from the castings 19 and carry ram boxes 25 which have hopper openings 26 and fuel delivery orifices 27. The retorts 11 may have bottom plates 28 and coal deflector plates 29 of conventional construction.

The above described stoker construction is substantially similar to that disclosed in my copending application, Serial No. 638,119, filed May 10, 1923 and assigned to the Westinghouse Electric and Manufacturing Company.

Mounted upon the lateral extensions 23 of the abutting castings 19 are hollow wall supporting castings 30, one casting 30 being disposed between each pair of retorts. The castings 30 are of T-shaped conformation, the hollow pedestals 31 of the casting having openings 32 for the ingress of air and the hollow cross arms 33 having openings 34 for the discharge of air. When assembled with other parts of the stoker the cross arms of the T-castings 30 abut and form a table 35 upon which the refractory portion 36 of the front furnace wall is supported. The pedestals 31 of the T-castings define with the retort elements fuel openings 38 registering with the fuel delivery orifices 27 of the ram boxes 25. The castings 30 further form closures for the forward ends of

the tuyère air boxes 15 with which the air chambers within the castings 30 freely communicate through the openings 32.

Removable front wall air-distributing boxes 40 are disposed rearwardly of and contiguous to the castings 30. The air distributing boxes 40 are of the same general conformation as the T-castings 30, pedestal portions 41, however, having rearwardly extending feet 42. The cross arms 43 of the air distributing boxes 42 are equal in width to the cross arms 33 of the castings 30 and when assembled about one another as shown in Fig. 3. Tuyère openings 45 in the cross arms 43 and tuyère openings 46 in the feet of the air-distributing boxes 40 are provided for the distribution of air within the furnace. It may be desirable in furnaces in which fuels having high moisture content, or fuels which ignite only with difficulty are employed, to omit the openings 45 in the cross arms 43 and to direct all the pre-heated air through the openings 46 into incoming fuel.

The manner in which the above described invention may be practiced is briefly as follows: In the construction of the front furnace wall, the forward end of the stoker grate is supported upon castings 19 which carry the angle beams 18 and the side plates 14. The lateral extensions 23 of the adjacent castings 19 are disposed at the forward ends of the tuyère air boxes 15 and serve as bases upon which the hollow wall supporting T-castings 30 are mounted. The T-castings are disposed along the front of the furnace, one between each pair of retorts, and form a table 35 upon which the refractory front wall 36 of the furnace is carried. The T-castings 30 form closures for the forward ends of the air boxes 15 and receive air therefrom through the openings 32. The air circulates upwardly through the pedestals 31 into the cross arms 33 of the T-castings 30 and passes out through the openings 34 into the cross arms 43 of the air-distributing boxes 40 where a part of the air may escape through the openings 45 into the furnace. The major portion of the preheated air should, however, preferably pass downwardly through the pedestals 41 and into the incoming fuel bed through the openings 46.

It is to be understood that the fuel from the ram boxes 25 is forced into the furnace through openings 38 and is distributed into the retorts and over the tuyère banks in the usual manner. It is apparent that the upper layers of green fuel upon entering the furnace are subjected to the blasts of the highly heated air from the openings 46 of the air-distributing box 40. The surface layers of the entering fuel, being thus subjected to a blast of heated air, are readily ignited. This is especially advantageous in furnaces burning fuels which ignite with

difficulty such as lignite, coke braize, or fuel having a high moisture content.

The construction above described has the further advantage of forming a rigid and durable furnace front wall, since the wall castings 30 rest upon the castings 19 and hence the retort elements, which at times need to be replaced, are free of the weight of the front wall and consequently may be removed without disturbing the front wall construction. Further, the circulation of air through the wall supporting castings maintains these members at a moderate temperature and cuts down any excessive expansion or contraction of these members under changes of furnace temperature. The refractory portion of the front wall is for this reason subjected to lesser lifting strains and is therefore capable of giving longer service.

While I have shown my invention in but one form, it may be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In an underfeed stoker furnace in which the side walls of spaced retorts carry tuyère members and define therewith air boxes alternating with the retorts, hollow castings closing the forward ends of the air boxes and formed to conduct air therethrough, and supplemental hollow cooperating castings formed to distribute air from the first mentioned castings into the forward portion of the fuel bed.

2. In an underfeed stoker furnace having alternately arranged series of tuyères and retorts, a ram box associated with each retort, hollow castings defining fuel openings from the ram boxes into the retorts, and air distributing members disposed rearwardly of the said hollow castings, said hollow castings and air distributing members being formed to conduct air therethrough and to the furnace.

3. In an underfeed stoker furnace in which the side walls of spaced retorts carry tuyère members and define therewith air boxes alternating with the retorts, hollow castings supporting the front refractory wall of the furnace and defining fuel openings into the retorts, and air distributing members disposed rearwardly of said hollow castings each provided with an expanded foot portion having air ports therein, said hollow castings and air distributing members being formed to conduct air therethrough to the incoming fuel.

4. In an underfeed stoker having a fuel supporting surface comprising alternating series of tuyères and retorts and air boxes

below the tuyères and between the retorts, castings at the forward end of the furnace supporting the retorts, hollow castings mounted upon the retort supporting castings to support the front refractory wall of the furnace, said hollow castings being so positioned as to close the ends of the air

boxes and receive air therefrom, and distributing members on the sides of the hollow castings adjacent the retorts. ¹⁰

In testimony whereof, I have hereunto subscribed my name this 29th day of May 1923.

OTTO ARAM.
